(57) **CLAIM**

The ornamental design for a gun accessory tool, as shown and described.

DESCRIPTION

FIG. 1 is a perspective view of the gun accessory tool of the present invention;

FIG. 2 is a top view of the present invention as shown in FIG. 1;

FIG. 3 is a front view of the present invention as shown in FIG. 1;

FIG. 4 is a bottom view of the present invention as shown in FIG. 1;

FIG. 5 is a back view of the present invention as shown in FIG. 1;

FIG. 6 is a right side view of the present invention as shown in FIG. 1; and,

FIG. 7 is a left side view of the present invention as shown in FIG. 1.

The portions of the drawing shown in broken lines are shown for environmental purposes and form no part of the claimed design.
